US0D1098374S

(12) **United States Design Patent** (10) **Patent No.:** **US D1,098,374 S**
(45) **Date of Patent:** **** Oct. 14, 2025**

(54) **FAUCET**

(71) Applicant: **Kohler Co.**, Kohler, WI (US)

(72) Inventors: **Tory Hayner**, Howards Grove, WI (US); **Ken Hanna**, Bellingham, WA (US); **Margaret Mazz**, Sheboygan, WI (US)

(73) Assignee: **Kohler Co.**, Kohler, WI (US)

(**) Term: **15 Years**

(21) Appl. No.: **29/991,495**

(22) Filed: **Feb. 28, 2025**

D374,706 S 10/1996 Doughty
D374,707 S 10/1996 Doughty
D374,708 S 10/1996 Doughty

(57) **CLAIM**

The ornamental design for a faucet as shown and described.

DESCRIPTION

FIG. 1 is a perspective view of the claimed design; FIG. 2 is a front view of the claimed design shown in FIG. 1; FIG. 3 is a rear view of the claimed design shown in FIG. 1; FIG. 4 is a side view of the claimed design shown in FIG. 1; FIG. 5 is another side view of the claimed design shown in FIG. 1; FIG. 6 is a top view of the claimed design shown in FIG. 1; and, FIG. 7 is a bottom view of the claimed design shown in FIG. 1.
The broken lines in the drawings depict portions of the faucet which form no part of the claimed design.

1 Claim, 7 Drawing Sheets
